TEMPLATE FOR APPLYING SLURS AND TIES
TO MUSICAL COMPOSITIONSJere B. O'Boyle, Annapolis, Md.
(242 Ivy St., San Francisco 2, Calif.)

Filed Sept. 15, 1960, Ser. No. 62,147

Term of patent 14 years

(Cl. D52—6)

FIG. 1 is a front elevational view of a template for applying slurs and ties to musical compositions, showing my new design;

FIG. 2 is a rear view thereof; and

FIG. 3 is an enlarged vertical cross-sectional view taken substantially on the line 3—3 of FIG. 1.

I claim:

The ornamental design for a template for applying slurs and ties to musical compositions, as shown.
